ELECTRIC SWITCH

Frank J. Russell, Wauwatosa, Wis., assignor to
Cutler-Hammer, Inc., Milwaukee, Wis., a corporation of Delaware

Application March 21, 1945, Serial No. 583,956

7 Claims. (CL 200—144)

1

This invention relates to electric switches and is particularly applicable to multi pole solenoid operated contactors which are capable of general use but are especially adapted for aircraft control.

Large aircraft of recent design are provided with control systems in which 3 phase A. C. current of relatively high voltage is used to operate various motor driven controls. In these systems it is necessary to effect control of the A. C. circuits by means of electromagnetic contactors which are capable of being controlled from remote points through the medium of direct current pilot circuits of low voltage. Contactors for this service must have various characteristics which may be briefly summarized as follows:

1. Small size and low weight in proportion to current handling capacity.
2. Ability to withstand severe vibration and large accelerating forces.
3. Ability to operate properly under a wide range of temperature, humidity or pressure conditions.
4. Completely enclosed to exclude dust from the contacts and operating mechanism.
5. Ability to operate properly under emergency load conditions.
6. Confinement and quick extinguishment of arcs.

The present invention has among its objects to provide a simple, rugged and inexpensive multi-pole solenoid operated contactor having the above noted characteristics.

Another object is to provide a contactor of the aforesaid character having a novel arc extinguishing and confining structure for the contacts of the several poles which is dust-tight and which renders the switch capable of interrupting exceedingly heavy currents without flashover arcing between the contacts of the various poles.

Another object is to provide an improved solenoid operating mechanism for contactors of the aforesaid type which is positive and reliable in operation and which provides for closure of the contacts without rebound.

Various other objects and advantages of the invention will hereinafter appear.

The accompanying drawings illustrate an embodiment of the invention which will now be described, it being understood that various modifications may be made in the embodiment illustrated without departing from the spirit and scope of the appended claims.

In the drawings;

2

Figure 1 is a side elevational view of a contactor embodying the invention;

Fig. 2 is an end elevational view of a contactor shown in Fig. 1;

5 Fig. 3 is a sectional view on line 3—3 of Fig. 2;

Fig. 4 is a diagrammatic view of the solenoid operating winding shown in Fig. 3 and a control therefor including an auxiliary switch shown in Figs. 2 and 3;

10 Fig. 5 is a sectional view on line 5—5 of Fig. 3;

Fig. 6 is a sectional view on line 6—6 of Fig. 5;

Fig. 7 is an isometric view of the contact enclosing parts illustrated in section in Figs. 3 and 5, and

15 Figs. 8 and 9 are perspective views of certain of the contactor parts illustrated in Fig. 3.

The contactor illustrated in the drawings consists of an operating assembly 1 and a contact assembly 2. Operating assembly 1 includes a

20 solenoid winding 3 and an associated magnetic plunger 4 which are carried by a pair of end supporting brackets 5 and 6. Contact assembly 2 includes a plurality of movable bridging contacts 7 each of which cooperates with a pair of

25 stationary contacts 8^a and 8^b. Stationary contacts 8^a and 8^b are mounted upon an insulating base 9 which is secured to the end brackets 5 and 6, and bridging contacts 7 are carried by an elongated insulating bar 10 which is operatively connected to plunger 4 by a pivoted operating lever 11. Base plate 9 has a removable insulating cover 12 mounted thereon, and as hereinafter set forth said base plate is provided with barrier projections which engage bar 10 and fit into recesses formed on the interior of said cover to provide individual arcing chambers for each of the stationary contacts 8^a and 8^b.

More specifically, solenoid winding 3 is mounted within a magnetic casing 13 of tubular form, and as shown in Fig. 3 said winding is wound upon a bobbin comprising a cylindrical brass tube 14 having a magnetic washer 15 fixed to the left hand end thereof and a non-magnetic washer 16 fixed to the right hand end thereof. Washer 15 is secured between a shoulder 17 and an inwardly extending flange projection 18 formed on the left hand end of casing 13 and washer 16 fits snugly within the right hand end of said casing. Brackets 5 and 6 are clamped against opposite ends of casing 13 by four bolts 19^a to 19^d, which extend between said brackets. These brackets are formed of magnetic sheet material and each is provided with a rectangular body portion *a* having parallel leg extensions *b* and *c* formed on opposite sides

30 of thereof. The body portions *a* of brackets 5 and 6

35

40

45

50

55

are provided with corner openings (Fig. 2) for receiving the bolts 18, and said brackets are so arranged that the leg extensions b and c thereof extend outwardly with respect to casing 13. Washer 16 is shouldered to fit within an opening 28 in the body portion a of bracket 6 and the left hand face thereof is shaped to provide an annular pole projection 21. A core plug 22, secured within an opening in the body portion a of bracket 6, extends into the right hand end of sleeve 14.

Plunger 4 is slidably supported within sleeve 14, and as shown in Fig. 3 the opposing faces of plunger 4 and core plug 22 are provided with drilled openings for receiving a coil spring 23. Upon energization of solenoid winding 3, plunger 4 is attracted against the action of spring 23 into engagement with core plug 22. Plunger 4 is provided with a magnetic ring projection 24 which seals with the face of pole projection 21 on washer 16 at the same time that the inner end of said plunger seals with core plug 22. The outer end of plunger 4 is provided with a grooved extension 26 for receiving operating lever 11.

As shown in Fig. 8, operating lever 11 comprises two sheet metal stampings secured together by spot welding and formed to provide a bifurcated end portion 28 which fits "snugly" within the grooved extension 26 on plunger 4. Said operating lever is also provided with a pivot pin 27 which is located midway between the ends thereof and as shown in Fig. 3 leg extension b of bracket 6 is slotted to receive said lever and is provided with indented bearing portions 28 on opposite sides of said slot for receiving said pivot pin.

Plunger 4 has an auxiliary switch 30 associated therewith, and as shown in Figs. 2 and 3 this switch comprises a stationary contact 31 and a cooperating movable spring contact finger 32, both of which are mounted upon an insulating plate 33. Plate 33 is arranged between the leg projections b and c of bracket 6 and is mounted upon two of the securing bolts 18^a and 18^b which extend beyond the body portion a of said bracket. Contact finger 32 is biased to normally engage stationary contact 31 and has an insulating operating pin 34 associated therewith which is slidably supported within a center opening in core plug 22. Pin 34 has an enlarged head 35 formed on the inner end thereof which is held in engagement with plunger 4 under the action of spring 23 to provide for movement of said pin with said plunger.

As shown in Fig. 4, solenoid winding 3 is adapted to be connected across a direct current supply circuit illustrated by lines L¹, L² by a pilot switch PS. Also as illustrated in this figure solenoid winding 3 is provided with coil sections 3^a and 3^b, the latter section being normally shunted by auxiliary switch 30. Thus upon closure of pilot switch PS coil section 3^a is energized to effect movement of plunger 4 toward its attracted position. However, prior to full movement of plunger 4 into its attracted position insulating pin 34 engages spring contact 32 to move the same into open position for connection of coil section 3^b in series with coil section 3^a. The current in coil section 3^a is reduced upon inclusion of coil section 3^b but when plunger 4 moves into its attracted position coil section 3^b acts cumulatively with coil section 3^a. Also upon movement of plunger 4 into its attracted position the holding force thereon is augmented by sealing of

ring projection 24 with the face of pole projection 21 on washer 16.

End bracket 5 is provided with a molded insulating cover member 54 which forms a closed chamber 38 for the front end of plunger 4, and endbracket 6 is provided with a similar cover member 64 which forms a closed chamber 39 for auxiliary switch 30. Each of these cover members fits tightly between the leg projections a and b of its associated bracket and is U-shaped to engage the body portion a thereof on opposite sides. Also each of these cover members is rendered dust-tight by means of a strip felt edging 48. As shown in Figs. 1 and 3, the bolts 18^a and 18^b are used to secure cover member 54 to its associated bracket 5 and the bolts 18^a and 18^b are used to secure cover member 64 to its associated bracket 6.

As hereinbefore set forth, contact assembly 2 includes a plurality of movable bridging contacts 7 carried by an insulating bar 10 and a plurality of pairs of stationary contacts 8^a and 8^b which are mounted upon an insulating base 9. Base 9 is rectangular in shape and is secured to the leg portions b of brackets 5 and 6 by screws 41. Insulating bar 10 is slidably mounted upon the upper face of base 9 for movement in a straight line parallel to the line of movement of solenoid plunger 4. In the embodiment illustrated contact assembly 2 is provided with three bridging contacts 7 and three pairs of stationary contacts 8^a and 8^b.

As shown in Figs. 5 and 6, insulating bar 10 is rectangular in shape and comprises two molded insulating sections 10^a and 10^b which are secured together at opposite ends by rivets 42. These sections are formed to provide equally spaced openings 43 for receiving the bridging contacts 7, and as shown in Fig. 5 each of said bridging contacts is yieldingly supported and held in assembled position upon bar 10 by a pin 44 and an associated spring 45. The opposing faces of insulating sections 10^a and 10^b are recessed to receive the pins 44 and springs 45 associated with bridging contacts 7, and said faces are also recessed to provide a slot 46 for receiving the upper end of operating lever 11.

Bar 10 is guided and supported within an elongated recess 47 formed in the upper face of base plate 9, and the stationary contacts 8^a and 8^b are arranged on opposite sides of said bar and to the left of their associated bridging contacts 7. As shown in Fig. 3, bar 10 is normally held in engagement with a shoulder 48 on the right hand end of recess 47 and upon movement of plunger 4 into its attracted position said bar is moved toward the left through the medium of lever 11 to effect engagement of bridging contacts 7 with their cooperating stationary contacts 8^a and 8^b. Upon full movement of bar 10 into its extreme left hand position, bridging contacts 7 are yieldingly held in engagement with their cooperating stationary contacts under the action of their associated springs 45.

Each of the stationary contacts 8^a and 8^b comprises a sheet metal stamping which is formed as shown in Fig. 9 to provide an elongated terminal portion 49. The terminal portions 49 of contacts 8^a and 8^b extend outwardly in parallel relation toward opposite sides of base 9 and are seated within recesses 50 (Fig. 7) formed in the upper face of said base. Each of the terminal portions 49 is secured to base 9 by a screw binding post 51 which is associated with the outer end thereof.

As hereinbefore stated, base 9 has a removable insulating cover 12 mounted thereon, and said base is provided with barrier projections which engage bar 10 and fit into recesses formed on the interior of said cover to provide individual arcing chambers for each of the stationary contacts 8^a and 8^b. As shown in Figs. 5 and 7, the top face of base 8 is formed to provide two rows of similarly shaped upwardly extending barriers 52 and 53 which are arranged in opposed relation on opposite sides of bar 10. Each of these rows includes end barriers 54 and 55 and two intermediate barriers 56 and 57. The barrier projections in row 52 extend outwardly from one side of bar 10 to provide spaced recesses for stationary contacts 8^a and the barrier projections in row 53 extend outwardly from the opposite side of said bar to provide spaced recesses for stationary contacts 8^b. Each of the barrier projections 54 to 57 has a right angle projection *a* formed on the inner end thereof for engaging bar 10.

Cover 12 is box-shaped to receive barrier projections 54 to 57 and is secured to base 9 by means of screws 58 carried by lug projections 59 formed on the upper face of said base. As shown in Fig. 7, the top wall of cover 12 is provided with an elongated recess 60 for receiving bar 10, and said wall is also provided with recesses 61 for receiving the upper ends of projections 54^a on barriers 54, recesses 62 and 63 for receiving the upper ends of barriers 56 and 57; recesses 64 for receiving barriers 55 and projections 65 for engaging barriers 54. Also the side walls of said cover are provided with recesses 66 for receiving the outer edges of barriers 55, 56 and 57. A heat resisting gasket 67 formed of asbestos sheet material is interposed between base 9 and cover 12 to provide a dust-tight joint between these parts.

As is apparent from the foregoing, the above described barriers form with bar 10 and cover 12 small individual arcing chambers for the several stationary contacts 8^a and 8^b. Base 9, bar 10 and cover 12 are preferably formed of molded melamine resin material, and in practice it has been found that by forming these parts of this material the contact enclosing structure is capable of handling exceedingly heavy arcing currents without flash-over between contacts of the various poles. While applicant does not desire to be restricted to any particular theory of operation of his arc extinguishing structure its effectiveness may extend at least in part to the use of melamine resin in the above mentioned parts which prevents what is known as arc tracking and also to the provision of small arcing chambers for the various stationary contacts.

It has been found that the above described solenoid operating mechanism effects closure of bridging contacts 7 without substantial rebound and also provides an exceedingly large operating force for moving said contacts into circuit closing position and for maintaining the same therein. Plunger 4 and bar 10 are so designed that the same are of equal weight. As hereinbefore stated, lever 11 is pivoted midway between its ends and it is thus apparent that accelerating forces which tend to move bar 10 and plunger 4 longitudinally are neutralized through the medium of said lever.

As hereinbefore stated, base 9 is secured to brackets 5 and 6 by screws 41. These screws extend through slotted openings in legs 5^b and 6^b of brackets 5 and 6 and are threaded into base 9. Thus by loosening screws 41 base 9 can be adjusted with respect to brackets 5 and 6 to vary the degree of movement of bar 10 upon energiza-

tion of solenoid winding 3. As is apparent from Fig. 3, upon adjustment of base 9 toward the right, plunger 4 is moved outwardly with respect to winding 3 to increase the degree of movement of bar 10, while adjustment of said base in an opposite direction has an opposite effect. Base 9 is adjusted with respect to brackets 5 and 6 by a pair of set screws 69. These set screws engage shoulders 70 formed on opposite ends of base 9 and are carried by brackets 71 fixed to the legs 5^b and 6^b of brackets 5 and 6.

The lower ends of the screw binding posts 51 are insulated from brackets 5 and 6 by a sheet of insulating material 72 which is interposed between said brackets and the underside of base 9. Also the upper ends of said binding posts are shielded by a pair of insulating cover members 73 which are secured to opposite sides of base 9 by screws 74. As shown in Figs. 3 and 5 solenoid winding 3 is provided with terminal leads 75 which are connected to screw binding posts 76 mounted upon the right hand end of base 9.

What I claim as new and desire to secure by Letters Patent is:

1. In a circuit controller, in combination, a stationary insulating base, a plurality of contact sets each including a pair of stationary contacts and a cooperating bridging contact, said bridging contacts being arranged in spaced parallel relation and said stationary contacts being fixed to said base, and an elongated insulating carrier for said bridging contacts located between said pairs of stationary contacts and guided and supported upon said base for reciprocation in a straight line to move said bridging contacts into and out of engagement with their associated stationary contacts, and a box-shaped insulating cover secured to said base and forming therewith a complete dust-tight enclosure for said contacts and said carrier, said carrier and its associated bridging contacts being held in assembled position upon said base by said cover member and said base being provided with barrier projections on opposite sides of said carrier which fit into recesses formed on the interior of said cover and form with said cover and said carrier individual arcing chambers of restricted volume for said stationary contacts.

2. A multi-pole switch comprising an elongated reciprocable slide bar of insulating material, a plurality of contact sets spaced longitudinally with respect to said bar and each comprising a pair of stationary contacts arranged on opposite sides of said bar and a cooperating bridging contact mounted transversely upon said bar, an insulating enclosure for said contact sets including a base member and a removable cover member, said stationary contacts being fixed to said base member and each pair thereof having integral terminal portions which extend outwardly and in opposite directions with respect to said bar through terminal outlets provided in opposite sides of said base member and said base member having walls which form with said bar and said cover member individual arcing chambers for each stationary contact together with a portion of its cooperating bridging contact, said chambers each wholly isolating the arcing occurring at each of the respective stationary contacts.

3. A multi-pole switch comprising an elongated reciprocable slide bar of insulating material, a plurality of contact sets spaced longitudinally with respect to said bar and each comprising a pair of stationary contacts arranged on opposite sides of said bar and a cooperating bridging contact mounted transversely upon said bar, an in-

7
sulating enclosure for said bar and said contact sets to which said stationary contacts are fixed, said enclosure having partitions and together with said bar forming for each fixed contact and the cooperating part of its bridging contact an individual isolating chamber, and said bar throughout its operating range having its opposite ends projected into closely fitting pockets formed in the walls of said enclosure to maintain said bar effective as an insulating barrier between said sets of stationary contacts in all operating positions of said bar.

4. As an arc extinguishing device for an electric switch of the class wherein circuit is closed and opened by bridging contacts moving into and out of engagement with pairs of stationary contacts, in combination, a common insulating movable carrier in which are transversely mounted said bridging contacts, and an insulating housing having barriers which interengage with said carrier to provide for each stationary contact and a portion of its associated bridging contact an individual arcing chamber, each of which chambers is isolated from the others for wholly isolating the arcing occurring between each of the stationary contacts and their associated bridging contacts.

5. A multi-pole switch comprising an elongated reciprocable slide bar formed of insulating material, a plurality of contact sets spaced longitudinally with respect to said bar, each of said contact sets including a pair of stationary contacts arranged on opposite sides of said bar and a cooperating bridging contact mounted transversely upon said bar, and an insulating enclosure for said contact sets including a base member and a 30 removable cover member, said base member having walls which form with said bar and said cover member individual arcing chambers for each of said stationary contacts and a portion of its cooperating bridging contact, each of said individual chambers being isolated from the others for wholly isolating the arcing occurring between each of the stationary contacts and their cooperating bridging contacts.

6. A multi-pole switch comprising, in combination, an insulating slide bar having a plurality of spaced bridging contacts transversely mounted thereon, end contact portions on each of said
